US0D1030675S

(12) **United States Design Patent** (10) **Patent No.:** **US D1,030,675 S**
(45) **Date of Patent:** **** Jun. 11, 2024**

(54) **ELECTRICAL TERMINAL**

(71) Applicant: **Hubbell Incorporated**, Shelton, CT (US)

(72) Inventors: **Craig Lawson**, Milford, OH (US); **Eric Miller**, West Chester, OH (US)

(73) Assignee: **Hubbell Incorporated**, Shelton, CT (US)

(**) Term: **15 Years**

(21) Appl. No.: **29/846,442**

(22) Filed: **Jul. 15, 2022**

(51) LOC (14) Cl. **13-03**

(52) U.S. Cl.

USPC **D13/133**

(58) **Field of Classification Search**

USPC D13/123, 133, 137.1, 137.3, 149, 151
CPC . H01R 11/12; H01R 4/34; H01R 4/36; H01R 9/18; H01R 4/302; H01R 43/048; H01R 4/182; H01R 4/20; H01R 43/058; H01R 11/09; H01R 11/05; H01R 4/62; H01R 9/2483; F16B 35/005; F16B 39/26; Y10T 29/53174; Y10T 29/53235; H02G 5/005; H02B 1/205; H02B 1/056

(57) **CLAIM**

The ornamental design for an electrical terminal, as shown.

DESCRIPTION

FIG. 1 is a front perspective view of the electrical terminal; FIG. 2 is a rear perspective view of the electrical terminal of FIG. 1;

FIG. 3 is a bottom perspective view of the electrical terminal of FIG. 1;

FIG. 4 is a left side view of the electrical terminal of FIG. 1;

FIG. 5 is a right side view of the electrical terminal of device of FIG. 1;

FIG. 6 is a top view of the electrical terminal of FIG. 1;

FIG. 7 is a bottom view of the electrical terminal of FIG. 1; FIG. 8 is a front view of the electrical terminal of FIG. 1; and,

FIG. 9 is a rear view of the electrical terminal of FIG. 1.

1 Claim, 6 Drawing Sheets
